UNITED STATES PATENT OFFICE.

GEORGE J. SCHADE, OF SANDUSKY, OHIO.

METAL-REINFORCED-CONCRETE COLUMN, POST, AND THE LIKE.

943,468.

Specification of Letters Patent.

Patented Dec. 14, 1909.

Application filed January 29, 1909. Serial No. 474,914.

To all whom it may concern:

Be it known that I, GEORGE J. SCILADE, a citizen of the United States of America, residing at Sandusky, in the county of Erie 5 and State of Ohio, have invented certain new and useful Improvements in Metal-Reinforced-Concrete Columns, Posts, and the Like; and I hereby declare the following to be a full, clear, and exact description of the 10 invention, such as will enable others skilled in the art to which it pertains to make and use the same.

This invention relates to metal-reinforced concrete columns, posts and the like, and has 15 for one of its objects the provision of a metal reinforcement which will render the column or section stronger and more reliable than the metal reinforced sections heretofore made.

20 A further object is the provision of a concrete column having a metal reinforcement which is inherently strong and rigid and consists of parts which can be easily and securely united or fastened together.

25 With these objects in view, this invention consists in certain novel details of construction and combinations and arrangements of parts hereinafter described, pointed out in the claims and illustrated in the accompanying 30 drawings.

In the said drawings, Figure 1 is a side elevation of a concrete column having a metal reinforcement arranged and constructed in accordance with my invention, the concrete portion of the upper part of the column being broken away. Fig. 2 is a transverse section substantially along the line 2—2, Fig. 1, looking downwardly. Fig. 3 is a vertical section of a portion of the metal 35 reinforcement, the section being taken substantially along the line 3—3 of Fig. 2, looking in the direction indicated by the arrow. Fig. 4 is a vertical section of a portion of the metal reinforcement, the section being taken substantially along the line 4—4, Fig. 3, looking inwardly. Fig. 5 is an elevation of one of the metal clips employed in holding together certain parts of the metal reinforcement.

40 The vertical metal-reinforced concrete column, shown in Figs. 1 and 2, may be of any shape but as here shown is rectangular in cross section, forming what is known as a square column.

45 The metal reinforcement for the column is of course embedded in the concrete 10 and

includes a group or plurality of vertical or substantially parallel upright rods 11 which preferably extend throughout the length of the column and are laterally spaced about 60 and equidistantly from the center of the column and a suitable distance from the outer surface of the column. Any number of these vertical rods may be employed but I have here shown four rods arranged in 65 rectangular formation opposite or diagonally inward from the different corners respectively of the column.

The vertical or longitudinally extending or parallel rods 11 are tied or secured together so as to provide a metal reinforcement of considerable inherent strength and stiffness, and the means which I employ for this purpose includes a rod 12 which is arranged spirally about the group of upright 70 and parallel rods and has its convolutions rigidly secured to and held in engagement with the outer sides of the said parallel rods. As here shown the spiral rod 12 or the convolutions thereof include portions 12^a which 75 are inclined with respect to the axis of the column and with respect to the vertical rods, as shown in Fig. 1, and are in planes parallel respectively to the sides of the column, as shown in Fig. 2, and portions 12^b arranged opposite the corners of the column 80 and inclined with respect to the axis of the column, as shown in Fig. 4, and inclined with respect to the sides of the column, as shown in Fig. 2, said portions 12^b being in 85 engagement with and crossing the different vertical or upright rods 11.

To secure the convolutions of the spiral rod 12 to the parallel rods 11, I employ sheet-metal clips, each of which is provided 95 with a central portion forming a loop 13 which is radially arranged relative to the center of the column and extends around the inner side of or receives one of the vertical rods 11, and having substantially parallel sides 14 and 15 which extend radially outwardly beyond the spiral rod and are thence doubled or returned inwardly, forming side loops 16 and 17, the outer sides of the side loops or the free ends 18 and 19 of 100 the clip being substantially parallel to the sides 14 and 15.

The outer portions of the clip which are formed by the two side loops 16 and 17 or the parallel sides 14 and 15 and 19 and 19 110 of the clip are provided with inwardly extending open slots 20 which, as shown clearly

in Figs. 1, 4 and 5, are inclined with respect to the axis of the column, and the two slots in the different side loops or outer portions respectively of the clip are arranged the one higher than the other and receive a section of one of the convolutions of the spiral rod, in this case receiving one of the portions 12^b of the rod. The slots 20 extend inwardly a sufficient distance to permit the portion 12^b of the spiral rod to bear inwardly against the outer side of the corresponding vertical rod 11.

To clamp or hold the convolutions of the spiral rod 12 against the rods 11, clamping members or securing devices, such, for instance, as tapered or wedge-shaped members 21 are inserted between the spiral rod 12 and the bases or central portions of the side loops 13 and 17 of each clip and are preferably driven into place so as to form a very rigid metal-reinforcing structure.

The clips and wedges will be employed for clamping or securing each convolution of the spiral rod 12 to all the vertical rods 11 so that the spiral rod is secured to each vertical rod at a large number of vertically spaced points.

I do not desire to be confined to the exact details shown but aim in my claims to cover all modifications which do not involve a departure from the spirit and scope of my invention.

What I claim is:—

1. A metal-reinforcement for concrete columns comprising a plurality of substantially parallel spaced rods, a rod arranged spirally about said parallel rods, and means securing said spirally arranged rod to said parallel rods and comprising a plurality of metal clips each of which is looped about the inner side and receives one of the parallel rods and has its sides extending outwardly and thence bent inwardly forming side loops, the outer portions of the clip having open inwardly extending slots which are inclined to correspond with and receive a portion of the spiral rod, and securing devices inserted between said portion of the spiral rod and the central portions of the side loops.

2. A metal reinforcement for concrete columns comprising a plurality of substantially parallel spaced rods, a rod arranged spirally about said parallel rods, and means securing the convolutions of said spiral rod to said parallel rods and comprising a plurality of metal clips, each having a central loop which receives one of the parallel rods and has side portions extending outwardly and thence doubled inwardly forming side loops, the outer portions of the clip having open inclined slots which extend inwardly and receive a portion of the spiral rod, and devices arranged to coöperate with the side loops in securing the said portion of the

spiral rod to the rod received by the first-mentioned loop.

3. In combination, a concrete section having a metal reinforcement comprising a plurality of spaced rods extending longitudinally thereof, a rod arranged spirally about said longitudinal rods, and means securing the convolutions of the spiral rod to the longitudinal rods and comprising a plurality of clips, each having a central portion which is looped about one of the longitudinal rods and has sides extending outwardly and thence returning inwardly forming side loops, the outer portions of the clip having open inwardly extending slots in which a portion of the spiral rod is received, and devices coöperating with the side loops in securing the said portion of the spiral rod to the adjacent longitudinal rod.

4. In combination, a concrete section having a metal reinforcement comprising a plurality of substantially parallel spaced rods extending longitudinally of the column, a spiral rod arranged about the said parallel rods, and means securing said spiral rod to the said parallel rods and comprising a plurality of metal clips, each having a central portion looped about one of the said parallel rods and having its sides extending outwardly and thence doubled or returned inwardly, forming side loops which have open inwardly extending slots which are inclined with respect to the corresponding parallel rod and receive a portion of the spiral rod, and devices arranged to coöperate with the side loops of the different clips in holding the convolutions of the spiral rod firmly against the aforesaid parallel rods.

5. In combination, a concrete column having a metal reinforcement comprising a plurality of substantially parallel spaced rods which extend vertically of the column, a spiral rod arranged about said vertical rods, and means securing the convolutions of the spiral rod to the different vertical rods and comprising a plurality of metal clips each of which receives one of the vertical rods and has substantially parallel side portions which extend substantially radially outwardly and thence return inwardly, forming side loops which have open slots which are inclined and receive a portion of the spiral rod.

6. A metal reinforcement for concrete columns and the like, comprising a plurality of substantially parallel upright rods; an inclined rod arranged to connect with the said parallel rods at different points vertically, and means securing the said inclined rods to the said parallel rods and comprising a plurality of metal clips, each having a loop which receives one of the parallel rods and has side portions which extend outwardly and thence return inwardly forming side loops which have open slots which are in-

clined to correspond with and be engaged by the inclined rod.

7. A metal reinforcement for a metal-reinforced concrete column, comprising a group of suitably spaced upright rods, a rod extending circumferentially of the said group of rods, and means securing the circumferentially extending rod to the rods of the said group of rods and comprising a plurality of metal clips, each having a central loop which receives one of the rods of the said group of rods and has side portions extending outwardly and shaped to form side loops which have open slots extending inwardly and receiving a portion of the circumferentially extending rod, and devices arranged to coöperate with the side loops in securing the said portion of the last-mentioned rod to the rod received by the first-mentioned loop.

8. In combination, a metal-reinforced concrete section having a metal reinforcement comprising a group of suitably spaced rods extending longitudinally of the section, a rod extending about and circumferentially of the said group of rods, and means securing the said circumferentially extending rod to the longitudinal rods and comprising a plurality of clips, each having a central portion which is looped about one of the longitudinal rods and has sides extending outwardly and shaped to form side loops

which have open inwardly extending slots in which a portion of the circumferentially extending rod is received, and devices co-³⁵ operating with the side loops in securing the said portion of the last-mentioned rod to the adjacent longitudinal rod.

9. A metal reinforcement for a metal reinforced concrete section, said reinforcement comprising a group of substantially parallel spaced rods, a rod surrounding the said group of rods, and means securing the said surrounding rod to the rods of the said group of rods and comprising a plurality of metal clips, each having a central portion looped about one of the rods of the said group of rods and having its sides extending outwardly and thence doubled or returned inwardly forming side loops which have open inwardly extending slots which receive a portion of the surrounding rod, and devices arranged to coöperate with the side loops of the different clips in holding the surrounding rod against the rod of the aforesaid group of rods.

In testimony whereof, I sign the foregoing specification, in the presence of two witnesses.

GEORGE J. SCHADE.
